UNITED STATES PATENT OFFICE

2,482,867

DISPENSING NOZZLE

Frederick C. Picut, Westfield, N. J., assignor to
Economy Faucet Company, Newark, N. J.

Application March 18, 1946, Serial No. 655,216

4 Claims. (Cl. 222—487)

1

The invention relates to liquid dispensing devices, adapted to be placed in a bottle or other receptacle, and provided with a spring closed valve and a vent pipe having a spring closed closure, which vent valve closure is opened when the discharge valve is opened, thereby allowing the discharge of liquid into a receptacle until the liquid level in the receptacle rises above the lower end of the vent pipe.

A further object is to provide the discharge valve with a valve stem extending upwardly and terminating in a shoulder on which a lip of the vent closure rests so the vent closure will be simultaneously opened when the discharge valve is opened, and spring means for forcing the vent closure to closed position when the discharge valve is seated. Also to provide an extension shaft on the discharge valve for engagement with the bottom of a glass for unseating the valve.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a side elevation of the dispensing device.

Figure 2 is a vertical transverse sectional view through the dispensing device.

Figure 3 is a top plan view.

Figure 4 is a horizontal sectional view taken on line 4—4 of Figure 2.

Figure 5 is a horizontal sectional view taken on line 5—5 of Figure 2.

Referring to the drawing, the numeral 1 designates a casing having a chamber 2 therein. Disposed within the chamber 2 is a frusto conically shaped valve 3 which seats on a similarly shaped valve seat 4. The valve 3, at its upper end, is provided with a spider 5 having guide lugs 6 for maintaining the valve substantially axially of the device, and also provided with spaced lugs 7 on opposite sides of the vent pipe 8, therefore it will be seen that the valve 3 will be axially guided in its upward and downward movement at all times. Extending upwardly from the spider 5 is a guide shaft 9, the upper end of which is slidably mounted in a bearing 10 in the arch member 11 carried by the upper end of the cylindrical sleeve 12.

The cylindrical sleeve 12 extends downwardly and terminates in a shoulder 13 within the upper

2

end of the casing 1, and held in the upper end of the casing 1 by the expansive action of spring 17 and in close engagement with the flange of the flanged bushing 14, and also held against rotation in relation to the casing 1 by lugs 15, which lugs are received in notches 16 of the annular shoulder 13. Valve 3 is normally maintained in seated position by means of an expansion spring 17, interposed between the spider 5 and the arch 11, clearly shown in Figure 2. Extending downwardly from the valve 3 is an actuating shaft 18, pressed against the bottom of a glass for unseating the valve 3 during a dispensing operation, and at which time the liquid passes from the receptacle at opposite sides of the arch 11, and thence downwardly through the sleeve 12 and valve casing chamber 2 to the receptacle. The upper end of the shaft 9 is provided with a reduced portion 19, slidably mounted in a bearing 20 of the arm 21 of the L-shaped arch supported bracket 22.

The reduced portion 19 of the shaft 9 forms a shoulder 23, the purpose of which will presently appear. Extending through one side of the device is a vent pipe 8, the lower end of which pipe curves downwardly and outwardly as at 24 through the side of the casing 1. It will be noted, that when the liquid level covers the lower end of the vent pipe, the discharge of liquid will be stopped, thereby preventing overflow and allowing the dispensing of a predetermined amount into the receptacle or glass, during the dispensing operation.

Slidably mounted on the upper end of the vent pipe 8 is a cylindrical closure valve 25 having an air port 26 in one side, and a washer 27 for closing the upper end of the vent. The lower end of the vent valve 25 is provided with an apertured ear, lip or lug 28, slidably mounted on the reduced shaft 19 and normally engaging the shoulder 23, and interposed between the shoulder 23 and the arm 21 is an expansion spring 29, which closes the vent valve when the discharge valve 3 is closed by the spring 17.

When the shaft 18 engages within the glass and the device forced downwardly for the discharge operation, the valve 3 is unseated and springs 17 and 29 are compressed, hence the vent valve is simultaneously opened with the opening of the discharge valve, and when pressure is removed from the shaft 18 both valves are simultaneously closed. Surrounding the sleeve 12 is a tapered stopper 30 when the device is used as a bottle attachment, and at which time it is placed in the neck of the bottle.

From the above it will be seen that a dispensing device is provided which is particularly adapted for dispensing liquor into glasses, and provided with compact means for simultaneously opening the discharge opening and inner end of the vent pipe, and also simultaneously closing the same.

The invention having been set forth, what is claimed as new and useful is:

1. A dispensing device for bottles comprising a casing having a chamber therein, means for attaching said casing to a bottle neck, a valve seat at the discharge end of said casing, a valve cooperating with said valve seat, an extension member carried by the valve and adapted to engage in a receptacle for unseating the discharge valve, an upwardly extending shaft carried by the inner end of said discharge valve and slidably mounted in a bearing carried by the inner end of the casing, an expansion spring surrounding said shaft for normally maintaining the discharge valve seated, a vent pipe within the casing to one side of the shaft, the lower end of said vent pipe extending through the side of the lower end of the casing above the valve, a closure valve for the upper end of the vent pipe, spring means for normally forcing said vent pipe valve to closed position, said vent pipe valve having an apertured lug through which the discharge valve shaft extends.

2. A dispensing device for receptacles comprising a chambered casing, said casing comprising a lower section, an upper section, interengaging connections between said lower and upper sections, means for maintaining said connections, the upper end of the upper section being open and provided with a transverse arch, a valve seat in the lower end of the lower section, a valve cooperating with said seat, said valve having a downwardly extending receptacle engaging shaft, an upwardly extending shaft within the casing carried by the valve and having a reduced portion at its upper end, an expansion spring surrounding said upwardly extending shaft between the arch

and the valve, a vent pipe within the casing to one side of the upwardly extending shaft and extending through the arch, a slidable vent closure valve carried by the upper end of the vent pipe, said vent pipe valve having an apertured lip through the aperture of which the upwardly extending shaft extends, an arm carried by the arch and in which the upper end of the reduced portion of the shaft is slidably mounted and an expansion spring interposed between the arm and the lip.

3. A device as set forth in claim 2 including a centering spider carried by the valve within the casing, said centering spider having spaced guide lugs on opposite sides of the vent pipe.

4. The combination with a dispensing device for liquid from a bottle, said device having an axially disposed discharge valve, a vent pipe to one side of the discharge valve, said discharge valve having an upwardly extending shaft, spring means for normally seating the discharge valve, of a slidable closure valve for the upper end of the vent pipe, said closure valve having an apertured lug through which a reduced portion of the upwardly extending shaft passes and spring means for normally forcing downwardly on said apertured lug whereby said vent valve will close and open with the seating and unseating of the discharge valve.

FREDERICK C. PICUT.
